TREATMENT OF HYDROCARBON OILS

Vladimir Ipatieff, Chicago, Ill., assignor to Universal Oil Products Company, Chicago, Ill., a corporation of Delaware

No Drawing. Application February 11, 1933,
Serial No. 656,271

1 Claim. (Cl. 260—168)

This invention relates to the treatment of hydrocarbon oils, and refers more particularly to the treatment of hydrocarbon oil mixtures of motor fuel boiling range produced by synthetic reactions though it may also be applied to fractions of similar boiling range resulting from the non-cracking distillation of primary crude oils, those produced by the re-running of these primary fractions and also motor fuels resulting from the cracking of heavier and less valuable portions of crude petroleums.

In a more specific sense the invention has reference to a process of treatment by means of which the sulfur content of sulfuric acid treated hydrocarbon products is efficiently reduced by means of a specific treating reagent.

Owing to the adoption of high compression ratios in automobile engines to increase their thermodynamic efficiency, a demand has been made upon the petroleum refining and other industries which furnish hydrocarbon motor fuels, for fuels of a high anti-knocking or slow-burning character. The cracking process which generally produces both unsaturated hydrocarbons and cyclic (including aromatic) hydrocarbons due to the dehydrogenating character of the decomposition reactions is employed quite generally to meet the demand for a high anti-knock motor fuel. However, complete control of the proportion of aromatics to olefins is not possible as the character of the charging oil varies with the type of crude oil from which they are produced, and when intensive cracking conditions are employed in an effort to increase the amount of aromatics and hence the anti-knock value, undesirably large losses in gas and coke are encountered and frequently the amount of olefins, particularly those of a highly unsaturated and unstable character, increases roughly in proportion to the increase in aromatics.

In order to conserve and stabilize the olefins produced in the cracking of heavy oils for the production of motor fuel, processes are employed in which they are caused to combine chemically with other hydrocarbons of an aromatic, naphthenic or paraffinic character in the presence of various catalysts which are effective in accelerating the rate of combination. In using sulfuric acid for this purpose there is evidence to indicate that intermediate compound formation occurs whereby sulfuric acid esters are formed on the one hand by direct addition of olefins to sulfuric acid and sulphenic acids on the other hand are produced by reactions analogous to the formation of benzene sulphonic acid from benzol. Further reaction between the esters and sulphenic acids thus initially formed results in the formation of alkylated hydrocarbons and a partial regeneration of the sulfuric acid.

60 The following equations typify the general

character of the reactions taking place between olefins and aromatics in the presence of a sulfuric acid catalyst:

The formation of products of a more highly substituted character than the mono iso-propyl benzol depends on a number of factors, particularly upon the strength of the acid and the temperature, both increasing strength of acid and increasing temperature favoring the formation of polysubstituted products.

The above equations typifying reactions between a particular olefin and benzol may be extended not only to include the interaction between any olefin and any aromatic but also to reactions between various olefins on the one hand and naphthenic and paraffinic hydrocarbons on the other hand. Thus, in contacting a straight run or cracked gasoline fraction with the olefin-containing gases from a cracking process in the presence of sulfuric acid, a certain amount of alkylation occurs as evidenced by the increase in anti-knock value and the proximate analysis of the products. In such cases, however, there is undoubtedly some concurrent polymerization among the olefins which increases as the reactivity of the other groups of hydrocarbons decreases.

In all of the reactions either of alkylation or polymerization in which sulfuric acid is used as the catalyst there is apparently an incomplete break-up of some of the sulfuric acid esters initially formed. While the major portion of these products remains dissolved in the sulfuric acid and this solubility can be maintained at a high point by proper choice of acid strength and operating conditions, a certain amount of these esters dissolves in the oil and is difficult to remove therefrom either by further sulfuric acid treatment or by the use of alkalies and extended washing. If the esters are not removed the sulfur content of the product is too high to meet commercial specifications and if redistillation is resorted to it is necessary to keep below a certain temperature by use of steam or vacuum to avoid decomposition of the esters and contamination of the overhead product with sulfur compounds of a more or less indeterminate character though they are apparently a mixture of organic sulfur compounds comprising sulfur ethers, sulpho-acids and sulfoxo compounds. In distilling with steam a certain amount of hydrolysis of the esters

occurs and altogether the treatment of such products becomes a problem of some importance.

In one specific embodiment the present invention comprises treatment of synthetic hydrocarbon mixtures produced by interacting olefins and other hydrocarbons in the presence of sulfuric acid by phosphoric acid to desulfurize them and produce other refining effects. The invention further comprises the use of graded mixtures of sulfuric and phosphoric acids for the same purpose.

The following equation shows the reaction which occurs between propylene (representing an olefin) and sulfuric acid:

20

The compound shown on the right of the equation typifies a number of esters of similar structure which as previously stated may remain dissolved in a liquid hydrocarbon mixture produced 25 by synthetic reactions between olefins and other hydrocarbons in the presence of sulfuric acid. According to the process of the present invention the hydrocarbon liquid containing such dissolved compounds is treated with phosphoric acid or the above mentioned graded mixtures of phosphoric and sulfuric acids, the course of the main reactions being evidently somewhat as follows:

40

The compounds on the right hand side of the equation are evidently soluble in the phosphoric acid employed in the treatments, at least up to a high concentration since as will be shown later a large quantity of hydrocarbon mixture containing 45 sulfuric acid esters may be treated before the equilibrium is reversed and the treating efficiency of the acid drops below an economical point.

45

The phosphoric acid ester remaining dissolved in the sludge acid mixture after treatment may 50 be hydrolyzed to produce alcohols, the following equation representing the reaction between water and the mono-iso-propyl phosphate shown above:

60

It will be obvious from the above equation that the phosphoric acid is regenerated and merely needs concentration by heating to bring it to a condition for further use. There are obviously some limits to this regenerating step since there are other compounds present which are of a less definite character than the phosphoric ester shown which may comprise a series of compounds not capable of hydrolysis. The proportion of such compounds will depend to a large extent on the nature of the reacting constituents which formed the synthetic hydrocarbon mixture in the presence of sulfuric acid.

A specific example of the results obtainable by a treatment comprised within the scope of the invention will be of assistance in showing its value in connection with the treatment of hydrocarbon oil mixtures containing sulfuric acid esters 5 and other organic products of sulfuric acid treatment.

The stock treated may have been produced as a result of treating a paraffinic straight run gasoline with olefin-containing gases from an oil 10 cracking plant in the presence of sulfuric acid. This stock may have a total sulfur content of 1.34% and at the same time have the approximate boiling range for motor fuel and not be distillable without decomposition of the sulfur 15 compounds to an extent which gives a percentage of sulfur in the overhead product greatly in excess of that allowed in commercial gasoline.

This gasoline stock may be treated with about 1% by volume of 89% phosphoric acid at a temperature of 50° C. The run may be made by treating successive 20% portions of the oil with the same acid, this method of operation simulating counterflow treatment. The sulfur content of the combined oil portions may be less 25 than 0.95% and after separation from the phosphoric acid sludge it may be distilled to produce a water white color and gum stable gasoline suitable for marketing. The 1% by volume of phosphoric acid used corresponds to the use of about 30 6 pounds of acid per barrel of stock treated which is a reasonable and practical figure when considered from an economic standpoint. When using sulfuric acid of commercial grade in treating cracked distillates or other hydrocarbon products 35 five pounds per barrel is considered a very mild treatment.

A further yield of gasoline is recoverable by 40 treating the phosphoric acid sludge with steam and also an amount of isopropyl alcohol approximately equivalent to the sulfuric acid esters corresponding to the 1.34 sulfur content, the alcohol being obtained by neutralizing and again distilling the sludge.

The process is therefore shown as a valuable 45 adjunct to synthetic processes in which olefins in the presence of sulfuric acid catalyst are caused to combine with other hydrocarbons. However, the process is also applicable to the treatment of sulfuric acid treated products from any source 50 such as acid treated cracked naphthas to remove therefrom the sulfuric acid esters which tend to decompose on redistillation of the naphtha and increase the sulfur content of the overhead gasoline as well as diminish the yield of boiling point 55 products by inducing polymerization reactions among the unsaturated components.

The foregoing specification and example will 60 serve their respective purposes of developing the character of the invention in showing its commercial value, but neither is to be considered as imposing undue limitations upon its generally broad scope.

I claim as my invention:

In the alkylation of aromatic hydrocarbons by 65 reaction thereof with olefin gases in the presence of sulphuric acid as a catalyst and wherein there is produced a hydrocarbon liquid containing dissolved sulphuric acid esters, the method of removing such dissolved esters which comprises treating said hydrocarbon liquid with phosphoric acid.

VLADIMIR IPATIEFF.
